UNITED STATES PATENT OFFICE.

FRANZ X. WAGNER, OF NEW YORK, N. Y., ASSIGNOR, BY MESNE ASSIGNMENTS, TO UNDERWOOD TYPEWRITER COMPANY, OF NEW YORK, N. Y., A CORPORATION OF NEW JERSEY.

RIBBON MECHANISM FOR TYPE-WRITING MACHINES.

SPECIFICATION forming part of Letters Patent No. 729,815, dated June 2, 1903.

Original application filed June 3, 1901, Serial No. 62,828. Divided and this application filed February 15, 1902. Serial No. 94,170. (No model.)

To all whom it may concern:

Be it known that I, FRANZ X. WAGNER, a citizen of the United States, and a resident of the borough of Manhattan, city, county, and State of New York, have invented a new and Improved Ribbon Mechanism for Type-Writing Machines, of which the following is a full, clear, and exact description.

My invention relates to type-writing machines, and has for its object to provide an improved ribbon operating and reversing mechanism which will be operated in conjunction with the mechanism which shifts the platen for upper or lower case printing.

The invention will be fully described hereinafter, and the features of novelty pointed out in the appended claims.

Reference is to be had to the accompanying drawings, in which—

Figure 1 is a longitudinal sectional elevation of a type-writing machine embodying my invention with parts omitted, so as to better disclose the elements constituting my invention. Fig. 2 is a detail plan view of the ribbon-reversing mechanism with a portion of the frame shown in section. Fig. 3 is a cross-sectional elevation of the machine. Fig. 4 is a detail rear elevation of one of the ribbon-spools and the adjacent parts of the machine. Fig. 5 is a detail outside view, partly in section, of a portion of the mechanism operated by the shift-key; and Fig. 6 is a view of the same parts looking from the other side.

1 designates the frame of the machine, and 35 2 the carriage, with the platen 3.

Upon the spindle 4, which supports the spring-drum 5, is mounted the ratchet-wheel 6, with which co-operates a pawl 7, normally maintained in engagement with the ratchet-wheel by a spring 8. The pawl 7 is pivoted to the drum 5, as indicated at 9, so as to rotate therewith. Connected with the ratchet-wheel 6 is a gear 10, meshing with another gear 11. This latter gear is secured to a shaft 45 12, the opposite end of which carries a bevel-gear 13. The bevel-gear 13 meshes with a bevel-gear 14, that is loosely supported upon a shaft 15. The bevel-gear 14 carries a sleeve

16, grooved, as indicated at 17, to receive the fingers 18, which are secured to a fixed portion of the machine. By this construction the gear-wheel 14 will at all times be maintained in mesh with its co-operating bevel-gear 13, notwithstanding any longitudinal movement of the shaft 15. Projecting from the shaft 15 is an arm 19, from which extends a pin 20, adapted to project into a slotted arm 21, connected with the sleeve 16. This construction will transmit a rotary motion from the bevel-gear 14 to the shaft 15, while leaving the said shaft free to move longitudinally. The shaft 15 is supported in suitable bearings 22 and is adapted to move therein longitudinally. Each end of the shaft 15 is provided with a clutch-section 23 and 24, respectively. 65 These clutch-sections are each adapted to co-operate with other clutch-sections 25 26. These clutch-sections 25 26 are secured upon shafts 27, extending in line with each other through suitable bearings in the framing of the machine, and the outer ends 28 of the shafts form supports for the ribbon-spools 29. An extension 30, which projects transversely of each shaft, is secured to rotate therewith. Each of these angular extensions 30 has pivoted thereto at 31 a latch 32, adapted to project through the corresponding ribbon-spool 29 to lock the same in place and to at the same time provide a handle by means of which the shaft can be rotated. Each of these latches 32 is spring-pressed and normally kept in locking engagement with the ribbon-spool, as indicated in Fig. 4. When it is desired to remove a spool from its shaft, it is merely necessary to press the latch 32 inward—that is, toward the shaft, thereby releasing the spool from the locking-shoulder 33 on the latch, so that the spool may be slipped off the outer end of its shaft. The position of the latch 32 at one side of the center of the ribbon-spool enables the said latch to be used as a crank for the purpose of turning the ribbon-spool and the shaft to which it is locked.

The shaft 15 is straddled by two arms 34, adapted to bear against the headed portions which carry or form the clutch-sections 23 24.

These arms 34 are each rigidly connected with a longitudinally-movable rod 35, which is under the tension of a spring 36, tending to force it outward, as indicated by the arrows 5 in Fig. 2. The free end of each rod 35 is connected by a pin-and-slot connection 37 with an angular lever 38. Each angular lever is pivoted at 39 to a fixed portion of the machine. Each of the arms 34 is provided with 10 an upwardly-extending bifurcated portion 40, which is adapted to receive a latch-lever 41, pivoted to a fixed portion of the machine, as indicated at 42. The lower face of each of these latch-levers is provided with a nose 43, 15 which is adapted to engage behind the bifurcated extension 40 to lock the spring-pressed rod 35 against the action of this spring. This latch-lever 41 extends into the path of an arm 44, which is carried by a vibratory frame 45, 20 pivoted at 46 to a fixed portion of the machine. The opposite end of this vibratory frame 45 is bifurcated, as indicated at 47, for the reception of the ribbon in its movement from one spool to the other.

25 The free end of each of the angular levers 38 extends into the path of a movable dog or pawl 48, which is pivoted to a vertically-movable slide 49. The front side of this pawl 48 is provided with a cam-face 50, which is 30 adapted to contact with a fixed abutment 51 and is maintained in engagement with said abutment by means of a spring 52. It will be observed that the cam-face 50 on the pawl will permit the latter to extend outwardly 35 beneath the free end of the angular lever 38 when the vertically-movable bar 49 is in its lowermost position and will permit the pawl to be withdrawn from a position where it will engage the angular lever as the bar 49 is elevated. The arrangement of the pawl is such 40 that the free end of either of the angular levers 38 will be engaged by the pawl 48 when the free end of the angular lever is in the lowermost position, as indicated in Fig. 5 of 45 the drawings. When, however, either of the levers is in the position indicated in full lines in Fig. 4, the pawl will obviously have no action on the angular lever upon the vertical movement of the bars 49. This result would 50 be obtained even if the pawl 48 were simply a projection rigidly secured to the bar 49. The purpose of employing a pawl which is allowed to swing out of the path of the angular lever 38 during the upward movement of 55 the bar 49 is to permit the lever 38 to be released and thrown into its lowermost position by the action of the spring 36 in case the bar 49 should be in its upper position at the time the latch-lever 41 is operated. The bars 49, 60 as before stated, are mounted to move vertically in the framing of the machine. The upper end of each of the bars 49 is adapted to support one end of the track 53, which supports the paper-carriage 2. The lower 65 end of each of the bars or slides 49 is connected with a link 54, which has its opposite

end secured to a bar 55, which is under the influence of a spring, the tension of which may be adjusted by the clutch-sections 56. Levers 57, which are fulcrumed on the bar 70 55, have suitable connections to shift keys of any appropriate type, and the rear ends of these levers are provided with arms 58, adapted to bear against cam-faces 59 of vibratory levers 60, pivoted to the frame at 61. It will 75 be understood that a lever 60 and a corresponding shift-key lever 57 are provided at each side of the machine adjacent to the vertically-movable slides 49. The upper end of each of the levers 60 is bifurcated, as indicated at 62, for the reception of a stud 63, carried by the slide 49. When the parts are 80 in the position indicated in Fig. 6, the lever 60 will coöperate with the stud 63, and the slide 49, which carries it, will prevent undue 85 vibration of the parts which support the platen 3. When either of the shift-keys is depressed, the rear end of the corresponding shift-key lever 57 will be elevated, thereby moving the corresponding lever 60 around its 90 pivot in the direction of the arrow in Fig. 6. This movement of the parts will bring the open mouth of the bifurcated portion of the lever 60 to a position where the stud 63 is 95 free to be moved upwardly in a vertical direction. As soon as the lever 60 has reached the limit of its upward movement the portion 64 of the lever will be moved beneath the stud 63 to prevent undue vibration of the lever 60 and the platen carried thereby 100 when the platen is in this elevated position. As soon as the key is released to permit the platen to assume the lowermost position the angular portion 58 of the lever 57 will, by its coöperation with the cam-face 59, permit the 105 stud 63 to assume the position indicated in Fig. 6. Thus I provide against undue vibration of the platen while it is being shifted either to the elevated or to the lowered position for the purpose of writing upper or lower 110 case characters, so that a blurring of the writing will not take place at those times. During the upward movement of the levers 57 just described each of them will be brought 115 into contact with a pin 65, which is carried by the corresponding slide 49. It will be seen 120 that a slight movement of the lever 57 is permitted before it reaches contact with the pin 65. This initial movement of the lever 57 is sufficient to throw lever 60 around its pivot 125 in the manner hereinbefore described in order to permit the stud 63 to pass out of the bifurcated portion of the lever 60. After the lever 57 has reached contact with its coöperating pin 65 it will move the slide 49 to elevate the platen. Oppositely-disposed set-screws 66 may be employed to regulate the 130 movement of the track 53 in both directions. A coiled spring 67 may be adjustably secured to the framing of the machine, as indicated at 68, and the opposite end of said spring may be connected with a projection 69 extending

from one of the links 54. This spring acts as a counterbalancing-spring for the platen and its supporting mechanism, which coöperates with the shifting mechanism to move the 5 platen for upper and lower case printing.

From the foregoing description it will be understood that the shift-keys will, through the pawls 48, operate the angular levers 38, and thereby compress the springs 36. During 10 the compression of these springs the slides or bifurcated arms 40 will be moved to positions where the corresponding gravity-latch levers 41 will drop to the lowermost position, thereby bringing the nose 43 on each 15 of these levers to the outside of the slide to lock the latter, as illustrated in Fig. 4, and thus to maintain the springs 36 under tension. When the springs are under tension, the free ends of the angular levers 38 are in the position indicated in Fig. 4. In this position each 20 of the angular levers will remain undisturbed and out of the path of the pawl 48 in its movement with the slide 49. If, however, either of the angular levers assumes the position indicated in dotted lines in Fig. 4, (which it assumes when its spring 36 is free from tension,) then the free end of said angular lever will be in a position to be engaged by the pawl 48, as indicated in Fig. 5. The next upward 25 movement of the slide 49 will elevate the free end of the angular lever, thereby compressing the spring 36 and locking it in compressed condition, as before described.

It has been hereinbefore pointed out that 30 the movement of the slides 40 effects a longitudinal movement of the shaft 15 to bring about an engagement of the coöperating clutch members at one side of the machine and a disengagement of the corresponding 35 clutch-sections at the other side of the machine. Thus, for instance, a longitudinal movement of the shaft 15 in the direction of the arrow α' in Fig. 2 will cause the clutch-section 23 to be disengaged from the clutch-section 25, and the clutch-section 24 will engage the clutch-section 26, so that further rotary motion transmitted to the shaft 15 will be communicated to the ribbon-spool 29 at the left-hand side of the machine. The 40 automatic reversal of the ribbon when an end thereof is approached will be brought about in the following manner: A suitable pin or abutment, which is carried by the ribbon near each end thereof, will contact with the 45 bifurcated portion 47, through which the ribbon passes. The contact between the pin of the ribbon and the bifurcated portion 47 of the frame 45 will cause said frame to be shifted around its pivot 46, thus elevating 50 the arm 44, which in turn will raise the corresponding gravity ratchet-lever 41 to free the slide 34, and thus move the clutch-sections to the position shown in Fig. 2. When the 55 other end of the ribbon is approached, a similar action will take place at the other side of the machine, and the shaft 15 will be moved

in the opposite direction to free the clutch-sections 24 and 26 and to engage the clutch-sections 23 and 25. Thus the right-hand spool will be placed in operative connection 70 with the ribbon-feed mechanism to rotate the right-hand ribbon-spool. It will be understood that any movement transmitted to either of the shift-keys will operate the shift-key levers 57 in the manner described to set 75 the corresponding spring 36 of the automatic ribbon-reversing device and that after said spring is placed under tension the mechanism is free from further coöperation with the pawl 48, which sets it until it has again been 80 released by the frame 45 in the manner described. It is obvious that a great number of operations by both shift-keys will take place for every movement of the mechanism which brings about the automatic reversal of 85 the ribbon, so that the springs 36 may be relied upon to be always under tension when it becomes necessary for them to bring about the longitudinal movement of the shaft 15 in the manner described. 90

I desire it to be understood that while I have described with great detail a specific embodiment of my invention I do not restrict myself to this specific construction, but the scope of my invention is to be determined 95 by the appended claims.

The mechanism described and shown in this application is also disclosed, but not claimed, in another application for Letters Patent filed by me on June 3, 1901, Serial No. 62,828, and 100 my present application is to be considered a division of the above-named prior application.

Having thus described my invention, I claim as new and desire to secure by Letters 105 Patent—

1. In a type-writing machine, the combination of an automatic ribbon-reversing mechanism which comprises two independently-movable operating members each adapted to 110 cause the ribbon to travel in one direction, springs for actuating said members, a separate latch device for each of said operating members, and means controlled by a movable part of the type-writing machine, for setting 115 the said operating members.

2. In a type-writing machine, the combination of automatic ribbon-reversing mechanism, and means controlled by the shift-key for setting said reversing mechanism. 120

3. In a type-writing machine, the combination of an automatic ribbon-reversing mechanism comprising two independently-movable members for causing the ribbon to travel in one direction or the other, springs for throwing said operating members, independent latches for holding each of said members against the tension of its spring, and means for releasing the operating members from their latches. 125

4. In a type-writing machine, the combination of a ribbon, spring-pressed automatic rib-

bon-reversing mechanism, means controlled by the platen-shift mechanism for setting said reversing mechanism, locking means for retaining the reversing mechanism in the set position, and means controlled by the ribbon for releasing said locking means.

5. In a type-writing machine, the combination of a ribbon, spring-pressed automatic ribbon-reversing mechanism, means controlled by the shift-key for setting said reversing mechanism, locking-latches for retaining the reversing mechanism in the set position and against its spring tension, and means operatively connected to the ribbon for releasing 15 one of said locking-latches when the end of the ribbon is approached.

6. In a type-writing machine, the combination of an automatic ribbon-reversing mechanism comprising two independently-movable 20 operating members for causing the ribbon to travel in one direction or the other, springs for throwing said operating members, an independent latch for each operating member, means operated by a movable part of the 25 machine for setting the operating members, and means for releasing the operating members from their latches.

7. In a type-writing machine, the combination of an automatic ribbon-reversing mechanism comprising operating members for causing the ribbon to travel in one direction or the other, springs for throwing said operating members, latches for holding said members, means for releasing said members from 35 the latches, levers connected with the operating members, a platen-shift mechanism, pawls movably carried by said platen-shift mechanism and adapted to engage the said levers, and means for causing said pawls to 40 swing out of the path of the said levers at the time the operating members are held in the set position by their latches.

8. In a type-writing machine, the combination of an automatic ribbon-reversing mechanism comprising operating members for causing the ribbon to travel in one direction or the other, springs for throwing said operating members, latches for holding the operating members in their set position, means, 45 controlled by the ribbon, for releasing the latches, a platen-shift mechanism, pawls pivoted to said mechanism, and provided with hooks, means having a tendency to throw said pawls in one direction, stationary guides 50 operating with said pawls to normally cause them to swing on their pivots when the platen-shift mechanism is operated, and levers connected with the said operating members and arranged to be engaged by the hooks of said 55 pawls to set the operating members, the pawls being free to swing out of the path of said levers after the operating members have been set.

9. Ribbon-reversing mechanism for type-writing machines comprising a rotary mechanism, a longitudinally-movable shaft which

is at all times in operative connection with the said rotary mechanism, two clutch-sections carried by said shaft, a clutch-section which is operatively connected to each ribbon-spool and which coöperates with one of the clutches on the shaft, spring-pressed means for moving said shaft longitudinally, latches for retaining said spring-pressed means against its spring tension, and means for releasing one of said latches when an end of the ribbon is approached.

10. Ribbon-reversing mechanism for type-writing machines comprising a rotary mechanism, a longitudinally-movable shaft which 80 is at all times in operative connection with the said rotary mechanism, two clutch-sections carried by said shaft, a clutch-section which is operatively connected to each ribbon-spool and which coöperates with one of the clutches on the shaft, spring-pressed means for moving said shaft longitudinally, 85 latches for retaining said spring-pressed means against its spring tension, means operated by one of the keys of the keyboard 90 for placing the spring-pressed means under tension, and means for releasing one of said latches when an end of the ribbon is approached.

11. In a type-writing machine, the combination of a platen, means for shifting said platen laterally for upper and lower case printing, and automatic ribbon-reversing mechanism, which is operatively connected to said platen-shifting means to set the former 100 when the shifting means are operated.

12. In a type-writing machine, the combination of a ribbon, a platen, means for shifting said platen laterally for upper and lower case printing, spring-pressed automatic ribbon-reversing mechanism, which is operatively connected to said platen-shifting means 105 to set the former against its spring tension when the shifting means are operated, and means, controlled by the ribbon, for releasing the reversing mechanism from its spring tension.

13. In a type-writing machine, the combination of an automatic ribbon-reversing mechanism, means for shifting the platen for upper and lower case printing, a device for setting said ribbon-reversing mechanism, a member loosely carried by the platen-shifting means and adapted to engage said setting device, mechanism for locking the platen-shifting means in one position, and means for moving said loose member out of the path 115 of the setting device when the platen-shifting means approaches the said position.

14. In a type-writing machine, the combination of automatic ribbon-reversing mechanism, means for shifting the platen for upper and lower case printing, a device for setting said ribbon-reversing mechanism, a member mounted to move with the platen when the latter is shifted and arranged to engage 125 and operate the said setting device, said mem-

ber being also capable of an additional movement to bring it out of the path of the setting device, mechanism for locking the platen-shifting means in one position, and means for moving said member out of the path of the setting device when the platen-shifting means approaches the said position.

In witness whereof I have signed my name to this specification in the presence of two subscribing witnesses.

FRANZ X. WAGNER.

Witnesses:

EUGENE EBLE,
JOHN LOTKA.
